UNITED STATES PATENT OFFICE.

EDWARD DESMON, OF DETROIT, MICHIGAN.

DIAMOND HOLDER.

Application filed June 19, 1922. Serial No. 569,375.

To all whom it may concern:

Be it known that I, EDWARD DESMON, a citizen of the United States, and residing at Detroit, in the county of Wayne and State of Michigan, have invented a new and Improved Diamond Holder, of which the following is a specification.

This invention relates to means for holding diamonds such as are employed in dressing grinding wheels, and its object is to provide a device of this kind which shall be universally adjustable so that it may be used to dress the face or either side of a grinding wheel as may be desired.

15 Grinding wheels are usually dressed by means of diamonds mounted in pedestals which are supported on carriages in such a manner that the diamond and its holder are carried across the working surface of the 20 wheel. Or the diamonds are mounted in the heads of shanks adapted to be secured in tool posts, and these tool posts in turn are mounted on the carriages. The various other ways for holding the diamonds are negligible.

In the present case the invention disclosed embodies a support having a pair of jaws and a pin rotatably mounted therein, a collar on the pin between the jaws, the collar 30 and pin having normally aligned holes to receive the stem of the setting for the diamond, together with means for forcing the pin longitudinally of the collar to lock the parts in the desired position.

35 This invention also consists in the details of construction illustrated in the accompanying drawing and particularly pointed out in the claims.

In the drawing, Figs. 1 and 2 are end and 40 front elevations of one form of diamond holder embodying my invention. Fig. 3 is a plan thereof. Fig. 4 is a section of the top of the holder shown in Figs. 1, 2 and 3, showing the setting for the diamond in position. Figs. 5 and 6 are side and top views 45 of a different type of holder embodying this invention.

Similar reference characters refer to like parts throughout the several views.

50 The pedestal 1 shown in Figs. 1 to 4 inclusive has a base 2 adapted to rest on a carriage of any well known construction and may be held thereon by means of a magnetic chuck, by a screw extending up from 55 the carriage into the threaded hole 3 in the base 2, or by clamps pressing down on the

base 2. These means for securing the pedestal to the carriage are in common use.

The upper end of the pedestal is formed with two jaws 4 and 5, spaced apart to receive the collar 6 and the two fibre washers 7 which prevent grit from reaching the pin 8. The jaw 4 has a hole sufficiently large to receive the larger part of the pin while the hole in the jaw 5 is adapted to receive the threaded portion 9. A nut 10, which may be knurled, engages this threaded end which may be of any desired diameter.

The pin 8 is formed with a hole 12 to receive the stem 13 and the collar 6 is also drilled to receive this stem. When the nut 10 is tightened it tends to slide the pin in the collar and in the jaws 4 and 5, which results in the stem 13 being firmly gripped and the collar being prevented from turning between the jaws.

On the outer end of this stem 13 is a knob or setting 16 in which the diamond 17 is mounted. When the nut 10 is slack, the stem 13 may be rotated in the hole 12 to bring any desired face of the diamond to operative position and the collar, pin and the setting for the diamond may be rotated, as indicated in Fig. 1, to position the diamond at any desired angle so that it may be used for dressing not only the face but the sides of a grinding wheel and may dress these sides at any desired angle. When the nut is tightened, the stem is locked in position.

When the setting is to be mounted at the end of a shank 20, this shank is also provided with jaws 21 and 22 to receive the pin 23 which extends through these jaws and through the collar 6 and washers 7 into the nut 24. The setting for the diamond is mounted in this pin and collar as before described and the parts may be so adjusted and locked that the diamond may extend at any desired angle from the axis of the shank. The shank may then be turned in the tool post so that the pin 23 will be at any desired angle.

The details of construction and the proportions and sizes of the several parts may all be changed by those skilled in the art without departing from the spirit of my invention as set forth in the following claims.

I claim:

1. A dressing device for grinding wheels comprising a pair of jaws, a collar rotatable between them, a pin rotatably and slidably mounted in the jaws and extending through

the collar, said collar and pin having alined holes, a stem mounted in said holes, a diamond mounted in the outer end of the stem, means to force the pin longitudinally of the collar to cause the collar and pin to grip the stem and rigidly hold the collar and stem relative to the jaws, and means to support said jaws.

2. A grinding wheel dresser comprising a support embodying a pair of jaws, a collar rotatable between the jaws, a pin slidable in the collar and jaws, a diamond setting engaged by the pin and collar, and means to move the pin relative to the collar and jaws to lock the collar and said setting in selected position.

3. A grinding wheel dresser comprising a base, a pedestal thereon and formed with a pair of perforated jaws at its upper end, a pin slidably and rotatably mounted in said jaws and having a threaded end, a collar mounted on the pin and rotatable therewith between the jaws, said pin and collar having alined holes, a stem rotatably

mounted in said holes, a diamond setting 25 at the outer end of the stem, and a nut on the threaded end of the pin to move the pin longitudinally of the collar and jaws to lock the parts.

4. A grinding wheel dresser comprising 30 a support, a pin mounted therein, a collar rotatable on the pin, said collar and pin having alined holes, a stem extending into said holes, and means to move the pin longitudinally in the collar to lock the support, 35 pin, collar and stem together.

5. A grinding wheel dresser comprising a support comprising a pair of jaws, a pin mounted therein, a collar rotatable on the pin, said collar and pin having alined holes, 40 a stem extending into said holes, means to move the pin longitudinally in the collar to lock the support, pin, collar and stem together, and fibre washers between the collar and the jaws to prevent the entrance 45 of grit.

EDWARD DESMON.
